UNITED STATES PATENT OFFICE.

WILLIAM A. SAULT, OF WORCESTER, MASSACHUSETTS.

AIR TRACK-SANDING APPARATUS.

1,028,079.

Specification of Letters Patent.

Patented May 28, 1912.

Application filed August 21, 1911. Serial No. 645,267.

To all whom it may concern:

Be it known that I, WILLIAM A. SAULT, a citizen of the United States, residing at Worcester, in the county of Worcester and State of Massachusetts, have invented a new and useful Air Track-Sanding Apparatus, of which the following is a specification.

The principal objects of this invention are to provide a practicable, simple and efficient form of sanding device especially suitable or street cars but applicable in part at least to railway locomotives; to provide an improved construction of receptacle for the sand arranged to sift the sand as it is thrown into it and to loosen the sand at the bottom by compressed air operated means to prevent clogging; to provide valve connections whereby the air from the system can be forced through the sand supplying pipes in such a way as to force the sand therewith along with great rapidity and uniformity, and means whereby when this connection is turned off or on another connection will be turned on momentarily to clear the pipes; to provide an improved form of nozzle for use in both parts thereof and capable of general use; to provide improved and simplified means whereby the connection between the receptacle and the discharge pipe above described can be cut off to permit repairs to either part; to provide an exceedingly simple arrangement for dividing the current of sand and air and directing part of it to each rail; to provide an improved form of flexible outlet nozzle which will permit the discharge of air through the walls thereof so as to allow the sand to be deposited on the rails without any more velocity than is due to the fall of the sand through a short space thus leaving the same in a quiescent state on the rails instead of blowing it therefrom as is the case with many types of sanders on the market.

The invention also involves improvements in details of construction in the various parts of the device, as will appear herein-after.

Reference is to be had to the accompanying drawings in which—

Figure 1 is a side view of a portion of a street car showing a preferred embodiment of this invention applied thereto. Fig. 2 is an enlarged side view of the sanding device showing the parts in section. Fig. 3 is an enlarged central vertical sectional view of

the main controlling valve therefor. Fig. 4 is a sectional view thereof on the line 4—4 of Fig. 3. Fig. 5 is a side elevation of the valve operating handle. Fig. 6 is an end elevation of the sand receptacle showing the means for operating the sand loosener. Fig. 7 is an end view of the sand loosener in the bottom of the sand box. Fig. 8 is a central longitudinal section view of the air discharging nozzle. Fig. 9 is a front elevation, with parts in section, of the discharge end of the system, and Fig. 10 is a perspective view of a detail thereof.

The invention is shown as connected up with the ordinary compressed air system 10, the details of which will not be referred to herein, as they may be of any ordinary or well known construction. As is the case with other types of sanders, this system is provided with a pipe 11, which is for the purpose of operating the sander. In this case this pipe communicates with a valve casing 12. This casing has a hollow boss or inlet 13 thereon into which the pipe 11 discharges. The main casing is of conical form and is provided with three outlets 14, 15, and 16. The hollow boss 13 has a pair of openings 17 and 18 opposite the outlets 14 and 15 respectively. The conical valve 19 which controls these ports is provided with a spring 20 for holding it against its conical seat, the opposite end of this spring being held by a cap 21 screwed into the end of the valve casing. This valve is provided with two passages 22 and 23, the former of which in one position of the valve connects the ports 17 and 14 and the other of which in another position of the valve connects the ports 18 and 15. This valve is provided with a release passage 24 communicating with the passage 23 so that when the valve is turned around to stop the operation of the machine, the last part of the motion will connect this release passage with the port and relieve the pressure of the cylinder. This valve is operated by a handle 25 having a socket 26 for receiving the square or other non-circular shaped end of the valve 19. The valve casing is provided with a set of notches 27 around the top thereof constituting a rack. Pivotally mounted on the handle itself over this socket is a spring-pressed latch 28 adapted to engage the teeth of this rack 27 and normally hold the handle at any position in which it is placed by the operator. At the same time on account of the spring

which holds the latch yieldingly in that position, the handle can be turned without any attention on the part of the operator to the disengagement of the latch from the rack. 5 The port 16 is connected with the port 18 by a passage 29 just about the time this release comes into action. The objects of these connections will appear hereinafter.

A box 30 for containing the sand or like 10 material for increasing the traction between the rails and car wheels is conveniently located in each front end vestibule of the car so as to be under control of the motorman. As shown the whole apparatus is located 15 upon the platform near the brake-staff thereof. The cylindrical sheet metal receptacle 30 has a round cast metal bottom 31 preferably bolted to the sides and standing on removable legs screwed to the floor 20 of the car. It is provided with a cap or top 32 which supports a screen box or shaker 33 on a hinge 34. The shaker is shown in this case as having a handle 35 projecting up through the cap which can be operated 25 to shake the screen. The cap is provided with a door 36 just over the screen through which the sand is introduced into the receptacle.

The port 15 communicates through a pipe 30 40 with a cylinder 41 and operates a spring-pressed piston 42. The rod of this piston is provided with a reciprocating rack 43. Loose on a shaft 46 is a ratchet wheel 47 with which the rack engages to operate the 35 ratchet wheel on each motion of the piston. This turns the shaft by means of a ball ratchet 45 fixed thereon. These parts are covered by a removable casing 44.

On the shaft are mounted radial arms or 40 pickers 49 inside the cast metal bottom. The hopper bottom being hemispherical in form the ends of the arms are arranged to come in the hemispherical surface so as to reach substantially to the surface of the 45 bottom in all positions of this loosener. The operation of this loosener will be obvious. When in closed position, its first operation is to connect the ports 18 and 15 and let air into the cylinder 41 to operate the loosener 50 first and loosen up the sand in the bottom of the hopper. The hopper bottom is shown as provided with a plurality of plugs 51 which can be removed to permit inspection and cleaning.

55. The bottom of the hopper discharges into a cast metal vacuum trap or ejector casing 52 which is secured directly to the nipple cast on the hopper bottom and is provided with a clean-out plug 52^a. In the passage 60 through which the sand descends is located an ordinary steam plug valve 53 ground cylindrically and having a port therethrough which can be closed by turning the valve part way around. This is to permit cutting 65 off the sand from the hopper from the cas-

ing 52 to allow inspection, repairs or the like. The first effect of turning the valve 19 from its closed position is to establish communication between the ports 17 and 14 and allow air to flow through a pipe 54 into a nozzle 55 centrally arranged at the end of the casing 52. This nozzle is provided with a cylindrical portion extending into the casing and with an enlarged passage 56 in the center. This passage has a smaller continuation at the end of the nozzle and at the extreme end it is reduced at 57 to form a small outlet port. The nozzle is provided with a plurality of conical elements 58 all preferably integrally united and each having a plurality of ports 59 all communicating with the passage 56 and extending at an angle to this passage so as to open in the base of the cone in which they are located. These passages are arranged 85 in a circle around the central passage and constitute a series of outlet ports conically arranged to permit the air to flow out along the conical surface of the next cone in front and to spread it sufficiently in each series of outlets to cause a substantially continuous conical jet of air to flow against the sides of the casing 52. It will be observed that this casing is contracted at its discharge end in a gradual manner so that it forms a surface converging toward the entrance of its outlet 60. This outlet is secured to a discharge pipe 61 by means of a union elbow 62 located on the floor of the car so that these parts can be disconnected from the 100 discharge without disturbing the latter or rendering it liable to become loose. The discharge pipe is connected with a clean-out casing 64 which has a nozzle 65 therein substantially like the nozzle 55. This nozzle 105 65 is supplied with a momentary blast of air through the pipe 66 and the port 16 just as the valve 19 is closed or opened. This is for the purpose of cleaning out the discharge hose 67 before and after using.

The discharge hose 67 is provided with a connection 69 having two opposite outlets 70 divided by a central separator wall 71 which projects toward the center of the hose 67 which is supported by springs 80 and discharges into this fitting. This provides for separating the same into two streams and directing them to the two rails. This fitting 69 is provided with a cap 72 which is attached to the main fitting by stove-bolts or the like which can be removed readily for inspection and repairs. Each one of these divisions discharges through a pipe 73 having an air valve 73^a and connected by an angular fitting or street elbow 74 with a threaded end located on the truck frame under the platform. At the end of this is screwed on, a downwardly depending close coiled spring 77 constituting a discharge outlet pipe. This spring has several 110 115 120 125 130 135

systems. In the first place, on account of the resiliency and the fact that its lower hinge free, it vibrates with the motion of the car so as to throw off moisture, snow, and the like. In addition to this, the convolutions of the spring allow the air which is forced through the pipe with the sand to be discharged laterally between them. There are no spaces between the convolutions sufficient to permit the sand to be discharged, but the provision of such an outlet for the air at a distance above the outlet for the sand causes the sand to lose its velocity due to the current of air and to be deposited on the rail simply with the velocity due to its fall through the conductor formed by the spring. This is an important feature because it causes the sand to be dropped quietly on the rails just in front of the wheels instead of blowing it on with a current of air and scattering most of the sand away from the rails.

From what has been said, it will be seen that the objects mentioned above are accomplished in an exceedingly simple and compact manner with this apparatus, and the mechanism itself is freely adjustable and readily inspected and cleaned.

While I have illustrated and described a preferred embodiment of the invention, I am aware that many modifications can be made therein by any person skilled in the art without departing from the scope of the invention as expressed in the claims. Therefore, I do not wish to be limited to all the details of construction herein shown and described, but

What I do claim is:

1. The combination with a car, of a sand hopper supported above the floor thereof and having a discharge outlet in the bottom, a horizontal ejector casing communicating at the top with said discharge outlet, a nozzle entering said casing for discharging air therethrough horizontally and drawing sand from said hopper, said casing having an outlet extending from the end thereof, and provided with a discharge conduit passing down through the floor of the car and being fixed to the floor, and means just above the floor for disconnecting the conduit.

2. The combination with a car, of a sand hopper supported above the floor thereof and having a discharge outlet in the bottom, a casing communicating at the top with said discharge outlet, a nozzle entering said casing for discharging air therethrough and drawing sand from said hopper, said casing having an outlet conduit passing through the floor of the car, a second casing just below the floor connected at its inlet end with said discharge conduit, and having a nozzle projecting into it, and a discharge pipe extending from the second casing.

3. In a sanding apparatus, the combina-

tion of a casing, a nozzle projecting into the casing for discharging air through the casing, a discharge pipe, a second casing having an inlet communicating with said discharge pipe and provided with a discharge outlet, an air blast nozzle extending into the second casing toward its discharge end, and means for connecting the nozzles with a source of compressed air.

4. In a sanding apparatus, the combination of a casing, a nozzle projecting into the casing, a discharge pipe, a second casing having an inlet communicating with said discharge pipe and provided with a discharge pipe at the opposite end thereof, an air blast nozzle extending into the second casing toward its discharge end, a compressed air supply pipe, means for introducing air into the first named nozzle to discharge a current of air and sand through the whole system, and means whereby when this connection is closed, a momentary blast of air will be sent through the second nozzle to clean out the connections beyond it.

5. In a sanding apparatus, the combination of a casing, a nozzle projecting into the casing, a discharge pipe, a second casing having an inlet communicating with said discharge pipe, an air blast nozzle extending into the second casing, a supply pipe for compressed air, two branch pipes, one connecting each of said nozzles, and a valve having a passage for connecting the supply pipe with the first named nozzle, and a passage for connecting the supply pipe with the second nozzle when the first nozzle is about to be shut off from connection with the supply pipe.

6. In a sanding device, the combination with a supply pipe, and a plurality of discharge pipes, of a valve having a passage in position to connect the supply pipe with one discharge pipe when the valve starts to turn and for turning off that connection upon the further turning of the valve, and means for connecting the supply pipe with another of said discharge pipes at that time, and means whereby after the second connection has been maintained the turning of the valve to shut it off will release the pressure therein and thereafter connect the supply pipe momentarily with a third discharge pipe.

7. In a sanding device, the combination with a conical valve casing having a supply pipe communicating therewith on one side and three discharge pipes communicating therewith on the other side, of a conical valve for said casing having a passage for connecting the supply pipe with one of the discharge pipes, a passage at an angle thereto for connecting the supply pipe with another of said discharge pipes, and having a release, and a third passage for connecting the supply pipe with the third discharge pipe.

- pipe when the second passage is being closed.
8. In a sanding device, the combination with a conical valve casing having an inlet and three outlets, of a conical valve for said casing having a non-circular end, and provided with a passage for connecting the inlet with one of the outlets, a passage at an angle thereto for connecting the inlet with another of said outlets and having a release, and a third passage for connecting the inlet with the third outlet when the second passage is being opened or closed, said casing having a notched end, and a handle for operating the valve having a socket for the non-circular end and provided with a spring-pressed latch for engaging the notched end, whereby the valve will be held in any position.
- 20 9. In a device of the character described, the combination with a compressed air supply pipe, of a hopper for receiving sand, a rotary loosener for the sand located in the hopper, means for rotating the loosener, and means connected with said supply pipe for operating the loosener rotating means when air is introduced through the supply pipe.
10. In a sanding device, the combination with a hopper having a discharge outlet, of a casing located below the hopper and in communication with said discharge outlet, a valve located between the hopper and casing, whereby the communication between them can be shut off, and a nozzle adapted to be connected with a source of compressed air or the like projecting into said casing, said casing having an outlet opposite the discharge end of said nozzle.
11. In a sanding device, the combination with a casing having an inlet at the top thereof and near one end, and a nozzle projecting into said end of the casing beyond the inlet, said casing having an outlet in line with the end of the nozzle, of means for introducing air into said nozzle, and means for loosening the sand above said inlet.
12. In a sanding apparatus, the combination with a compressed air supply pipe and a hopper for receiving the sand, of a shaft located near the bottom of the hopper, arms mounted on the shaft, a ball ratchet wheel on the shaft, a reciprocable rack for operating the ratchet wheel, a cylinder adapted to receive compressed air from said pipe, and a piston in said cylinder for operating the rack.
13. In a sanding device, the combination with a hopper having a top for receiving sand, of a sifter located directly under the top, and pivoted on one side thereof and having a handle projecting up through the top for operating it, a bottom for the hopper having an outlet at the center thereof, and a valve for introducing air below the bottom of the hopper to discharge the sand therefrom.
14. In a sanding device, the combination with a hopper having a top for receiving sand, of a sifter located directly under the top and pivoted on one side thereof and having a handle projecting up through the top for operating it, and a concave bottom for the hopper having an outlet at the center thereof and provided with clean out plugs.
15. In a sanding device, the combination of a casing having an inlet extending vertically downwardly at one end thereof, a nozzle projecting in horizontally from the same end of the casing under the inlet and beyond it, and an outlet in line with the nozzle, said nozzle being provided with means for directing a plurality of jets of air angularly from the axis thereof toward the outlet.
16. In a sanding device, the combination with a casing having an inlet and an outlet, of a nozzle projecting toward said outlet and extending through the main part of the casing, said nozzle being provided with a plurality of conical enlargements arranged end to end and having discharge orifices extending through said conical enlargements each in position to discharge the air along the surface of the next conical surface in front.
17. As an article of manufacture, a nozzle for an air blast system having a plurality of conical surfaces arranged end to end in a series, each having discharge orifices in position to discharge the air along the next conical surface.
18. As an article of manufacture, a nozzle for an air blast system having a plurality of conical surfaces arranged end to end in a series, each having discharge orifices in position to discharge the air along the next conical surface, and having a discharge orifice in the end and a passage up to the last named discharge orifice of larger area than any of said orifices.
19. In a sanding apparatus, the combination of a casing, a nozzle projecting into the casing for discharging air through the casing, a discharge pipe, a second casing having an inlet communicating with said discharge pipe and provided with a discharge outlet, an air blast extending into the second casing toward its discharge end, means for conducting the air and sand away, and for dividing the current and delivering it in two streams, and means for connecting the nozzles with a source of compressed air.
20. In a sanding device, the combination with a pipe for discharging a current of air and sand, two divisions therefor, and a three-way fitting connecting said supply pipe with the two divisions and having a

wall for dividing the current of sand and air, said fitting being provided with a removably mounted side constituting substantially a half of the fitting.

5 21. As an article of manufacture, a discharge nozzle for a sanding device comprising a pipe having a coiled spring at the end thereof through which the sand can be discharged and between the coils of which 10 the air can escape.

22. As an article of manufacture, a discharge nozzle for a sanding device comprising a pipe having depending therefrom a

coiled spring free at the bottom whereby the sand will be discharged therethrough and 15 the air will pass between the coils thereof between the convolutions of the spring to cause the said sand to lose its velocity due to the current of air.

In testimony whereof I have hereunto set 20 my hand, in the presence of two subscribing witnesses.
